UNITED STATES PATENT OFFICE.

FRED MC LAUREN BROOKES, OF FAYETTEVILLE, ARKANSAS.

WINDING AND MEASURING MACHINE.

1,024,246.

Specification of Letters Patent. Patented Apr. 23, 1912.

Application filed March 21, 1911. Serial No. 615,925.

To all whom it may concern:

Be it known that I, FRED M. BROOKES, a citizen of the United States, and a resident of Fayetteville, in the county of Washington, 5 ton and State of Arkansas, have invented a new and Improved Winding and Measuring Machine, of which the following is a full, clear, and exact description.

The object of the invention is to provide 10 a new and improved winding and measuring machine, for use in stores and other places, and arranged to facilitate the unwinding of a piece of screen wire cloth or other fabric from a roll, to measure the unrolled portion 15 according to the length desired by a customer, to rewind the unrolled piece and cut it off from the roll at the desired length, and to allow of splicing the end of a roll of fabric to a remnant from a previous roll.

20 For the purpose mentioned, use is made of an unwinding roller, a winding up roller, a pivoted cutting and splicing beam intermediate the said unwinding roller and the said winding up roller, and a measuring device 25 vice arranged for co-action with the said cutting and splicing beam to measure the length of a piece of fabric unwinding from the unwinding roller and winding up on the said winding up roller.

30 A practical embodiment of the invention is represented in the accompanying drawings forming a part of this specification, in which similar characters of reference indicate corresponding parts in all the views.

35 Figure 1 is a front elevation of the machine; Fig. 2 is an enlarged cross section of the same on the line 2-2 of Fig. 1, and showing a piece of screen wire cloth in position for unwinding, winding up and measuring; Fig. 3 is a similar view of the machine and showing a piece of poultry fence wire in position to be unrolled, wound up and measured; Fig. 4 is a side elevation of the machine and showing the ends of adjacent pieces spliced together; Fig. 5 is an enlarged perspective view of the cutting and splicing beam; Fig. 6 is an enlarged perspective view of the body of the winding up roller; Fig. 7 is an enlarged longitudinal section of the winding up roller; Fig. 8 is a face view of the trunnion at one end of the winding up roller; Fig. 9 is a like view

of the trunnion at the other end of the winding up roller; Fig. 10 is a plan view of the same; Fig. 11 is an end view of the winding up roller and showing more particularly the pawl and ratchet mechanism for holding the winding up roller against accidental return movement; Fig. 12 is a face view of one of the collars adjustably held on the unwinding roller, the latter being shown in section; Fig. 13 is a cross section of the same on the line 13-13 of Fig. 12; Fig. 14 is a face view of the same and showing the parts in unlocked position; and Fig. 15 is a face view 65 of a modified form of the cutting and splicing beam.

On a suitably constructed frame A are arranged bearings B, in which is journaled an unwinding roller C for unwinding a roll 70 of screen wire cloth D or other fabric, the unwound portion passing up over a guide roller E journaled on the main frame A, and then the unwound portion extends over a beam F and finally onto a winding up 75 roller G journaled on the main frame A. The screen wire cloth D during its passage over the beam F is in contact with a measuring device H, of any approved construction mounted on an arm H' pivoted on the main 80 frame A, so as to permit of swinging the said measuring device into or out of measuring position relative to the cloth D, as indicated in full and dotted lines in Fig. 2, see also Fig. 4. The measuring device H is 85 preferably provided with a wheel H² rolling on the upper surface of the cloth D, as the latter passes over the beam F, and the said wheel H² actuates mechanism connected with pointers H³, H⁴, indicating feet and 90 inches on a dial H⁵, so that the user of the machine can readily see how much of the screen wire cloth has been unwound from the roller C and wound up on the roller G. Thus when a customer desires a certain 95 length of screen cloth D, the operator winds up the screen cloth on the winding up roller G until the pointers H³, H⁴ indicate the desired length, and then the operator swings the measuring device H upward into an inactive position, as shown in dotted lines in Fig. 2, and in full lines in Fig. 4, and then the operator cuts the screen wire cloth D transversely along a groove F' in the top of 100

the beam F, and which groove is opposite the contact of the wheel H² with the screen cloth D.

The bearing B for the roller C is preferably connected by hinges I with the main frame A, and the roll of wire screen cloth D on the roller C is engaged by one or more springs J attached to the main frame A, and serves to prevent the roll of wire screen cloth from unrolling too fast.

On the roller C are adjustably secured flanges or collars K, adapted to abut against the ends of the roll of wire screen cloth D held on the roller C. Each of the collars K is provided with a cut-out portion K' (see Figs. 12, 13 and 14), in which extends a clamping plate L, hung on an eccentric or a cam N, journaled in a bearing O attached to the back wall of the cut-out portion K', and the said eccentric or cam N is provided with a handle N' adapted to be taken hold of by the operator, to turn the eccentric or cam N, with a view to move the clamping plate L in or out of clamping engagement with the roller C. The side walls of the cut-out portion K' of the collar or flange K serve to limit the swinging motion of the handle N', as will be readily understood by reference to Figs. 12 and 14.

When the eccentric or cam N is in the position shown in Fig. 14, the clamping plate L is lifted out of engagement with the roller C, so that the collar K can be shifted lengthwise on the roller C until the desired position is reached, and then the operator swings the handle N' over into the position shown in Fig. 12, so that the clamping plate L moves into clamping engagement with the roller C, to lock the collar or flange K in position on the roller C.

The winding up roller G has its body preferably made in two sections G', G², removably connected with trunnions P and Q, journaled on the main frame A, and of which the trunnion Q is provided with a crank arm R under the control of the operator for turning the winding up roller G, to wind up the wire screen cloth D as previously mentioned.

In order to removably connect the body sections G' and G² of the winding up roller G with the trunnions P and Q, the following arrangement is made: On one end of the body sections G' and G² are arranged lugs G³, adapted to engage a slot P' formed in a collar or a flange P², integral with the trunnion P, and one of the said lugs G³ is pressed on by a pin P³ mounted to slide in the collar P² and pressed on by a spring P⁴, as will be readily understood by reference to Figs. 7 and 8. By the arrangement described, the lugs G³ are held firmly in place in the slot P' of the flange P² of the trunnion P. The opposite end of the body sections G', G² are provided with lugs G⁴ simi-

lar to the lugs G³, and adapted to engage a slot Q' formed in a collar or a flange Q², attached to or forming an integral part of the trunnion Q. The slot Q' extends at one end to the periphery of the flange or collar Q², so as to permit of conveniently placing the body sections G', G² with their lugs G³ and G⁴ in position in the slots P' and Q' of the trunnions P and Q, or to remove the said body sections from the said parts. Now when the body sections are in position on the trunnions, then a retaining block Q³ is moved into the open end of the slot Q' so as to lock the lugs G⁴ in place in the slot Q'. The block Q³ is attached to an arm Q⁴ projecting from a spindle Q⁵ mounted to turn in the flange or collar Q², as plainly shown in Figs. 9 and 10. Into the opposite or closed end of the slot Q' extends a pin Q⁶ held on a spring Q⁷ attached to the collar Q², so that the lugs G⁴ are engaged by the block Q³ and the pin Q⁶, to hold the lugs in place on the collar Q². When it is desired to remove the body sections G', G² from the trunnions P and Q then the operator swings the arm Q⁴ outward so as to move the block Q³ out of the slot Q', to permit of lifting the end of the body sections G', G², having the lugs G⁴ out of engagement with the collar Q², and by moving the body sections G', G² in the direction of their length the lugs G³ are disengaged from the slot P' of the flange P² of the trunnion P. The outer end of the wire screen cloth D is passed between the sections G' and G², as plainly indicated in Fig. 2, so that the terminal of the cloth is clamped between the two sections, it being understood that sufficient pressure is exerted by the spring-pressed pins P³, Q⁶ to clamp the end of the wire screen cloth in place between the sections. When the operator now turns the crank arm R, the roller G is turned to wind up the wire screen cloth, and when the desired length of cloth has been wound up on the roller G and the cloth is cut along the groove F', as previously mentioned, then a string is tied around the rolled up portion, after which the roller G is disconnected and removed from the trunnions P and Q, as previously explained, to permit of sliding the measured and the rolled up and tied piece of wire screen cloth off of one end of the body sections G' and G² of the roller G. The sections G' and G² can then be replaced in position on the trunnions P and Q. On the trunnion Q is secured a ratchet wheel S, engaged by a pawl S' fulcrumed on the main frame A, to prevent accidental return movement of the winding up roller G.

In order to cut a roll of poultry or large mesh wire D' besides the roll of wire screen cloth D, as before mentioned, use is made of a second unwinding roller U journaled on

fixed bearings B' held on the main frame A below the hinge bearings B. The unwinding roller U is provided with adjustable collars V, similar to the collars K, and 5 adapted to engage the ends of the roll of poultry wire, the same as the collars K engage the roll of wire screen cloth D.

In order to prevent the wire D' from interfering with the screen wire cloth D, 10 mounted on the roller C, the latter is lifted off its bearings B, and then the latter are swung inward on the hinges I, so as to bring the second set of bearings B² in position for receiving the roller C, as will be understood 15 by reference to Figs. 1 and 4, the said bearings B² being attached to the sides of the bearings B. The poultry wire D' is passed upward over the guide roller E and the beam F, to wind up on the roller G (see 20 Fig. 3), the same as the wire screen cloth D previously mentioned. One or more springs J' bear against the peripheral face of the roll of poultry wire D' to prevent 25 too rapid unwinding of the poultry wire D'. In order to permit of splicing the adjacent ends of two pieces of poultry wire D² and D³, of which the piece D² unwinds 30 from the roller U while the piece D³ has been wound up on the winding up roller 35 G and forms part of a previous roll, use is made of the beam F, which is provided at its ends with trunnions F² journaled in the main frame to permit of swinging the beam F up into a vertical position, as shown in 40 Fig. 4. The upper end of the beam F is provided with retaining devices in the form of hooks F³, as shown in Figs. 4 and 5, or in the form of clamps F⁴, as indicated in Fig. 15. Now the end of one of the pieces 45 D² or D³ is engaged with the retaining devices F³ or F⁴, and then the adjacent end of the other piece D³ or D² is spliced onto the end engaged by the retaining devices 50 F³, by interlocking the wires with each other as is now practised. By having one end fastened to the beam F, it is evident that the other end can be readily spliced to the fastened end, and then the beam F is swung 55 back to its normal horizontal position, after 60 which the measuring device H is lowered so as to allow of winding up more poultry wire on the roller G according to the length demanded by the customer.

From the foregoing it will be seen that 55 by the arrangement described a piece of wire screen cloth or other fabric can be readily unwound and measured according to the length desired by a customer, at the same time winding up the other end and 60 permitting convenient cutting off of the fabric from the original or main roll. It will also be noticed that different fabrics are accommodated on the machine and either 65 can be unwound for measuring off a certain length, cutting it and rewinding it as above

explained, and in case a roll has run out without furnishing a desired length then the second roll can be placed in position on the machine and the outer end thereof spliced to the terminal of the portion held 70 wound up.

The machine is simple in construction, takes up comparatively little space and can be easily manipulated for the purpose.

Having thus described my invention, I 75 claim as new and desire to secure by Letters Patent:

1. In a winding and measuring machine, a pivoted cutting and splicing beam provided with means for holding the end of a 80 fabric, a pivoted measuring device above the said beam, and means for drawing a fabric over the beam to operate the measuring device.

2. A winding and measuring machine, 85 comprising a frame, an unwinding roller for carrying a roll of fabric material and journaled on the said frame, a winding up roller journaled on the said frame, manually-controlled means for turning the said winding up roller, a measuring, cutting and splicing beam pivoted on the said frame intermediate the said rollers, and having means whereby the end of a fabric may be held, 90 and a measuring device opposite the measuring, cutting and splicing beam and having an actuating wheel operated by the fabric passing over said beam, said measuring device being mounted to swing on the said frame into and out of operative position 95 100 relative to the said beam.

3. A winding and measuring machine, comprising a frame, an unwinding roller for carrying a roll of a fabric material and journaled on the said frame, adjustable collars 105 on the said unwinding roller, a winding up roller having a sectional body, and trunnions journaled in the said frame, the sectional body being removably connected with the said trunnions, a beam pivoted on the 110 said frame intermediate the said rollers, the said beam having a longitudinal groove and retaining means for holding one end of the fabric, and a measuring device having arms pivoted on the said frame for swinging the 115 measuring device into and out of operative position relative to the said beam.

4. A machine of the class described, comprising a frame, an unwinding roller journaled on the said frame, a winding up roller 120 journaled on the said frame, and a pivoted cutting and splicing beam mounted on the said frame intermediate the said rollers, the cutting and splicing beam having a groove in one side, retaining means on one edge for 125 engagement by one end of a fabric to be spliced to another fabric.

5. A machine of the class described, comprising a frame, two unwinding rollers for carrying different fabrics, fixed bearings on 130

- the frame for one of the unwinding rollers, bearings hinged on the said frame for the other unwinding roller, a second set of bearings carried by the hinged bearings, a guide roller journaled on the frame, a beam pivoted on the said frame adjacent the said guide roller, and a winding up beam having a body and trunnions detachably connected with the said body, the said trunnions being 5 journaled on the frame, and the said guide roller and the said beam being intermediate the said unwinding roller and the said winding up roller.
6. A machine of the class described, comprising a frame, two unwinding rollers for carrying different fabrics, fixed bearings on the frame for one of the unwinding rollers, bearings on the said frame for the other unwinding roller, a guide roller journaled on 10 the frame, a beam pivoted on the said frame adjacent the said guide roller, a winding up beam having a body and trunnions detachably connected with the said body, the said trunnions being journaled on the frame, and 15 the said guide roller and the said beam being intermediate the said unwinding roller and the said winding up roller, and a measuring device having arms pivoted on the said frame to permit of swinging the said 20 measuring device into and out of operative position relative to the said beam, said measuring device having an actuating wheel operated by the material passing over said beam.
- 30 7. A machine of the class described, comprising a frame, two unwinding rollers for carrying different fabrics, a fixed bearing on the frame for one of the unwinding rollers, a bearing hinged on the said frame for the 35 other unwinding roller, a guide roller journaled on the frame, a beam pivoted on the said frame adjacent the said guide roller, a winding up beam having a body and trunnions detachably connected with the said body, the said trunnions being journaled on 40 the frame, and the said guide roller and the said beam being intermediate the said unwinding roller and the said winding up roller, and springs mounted on the said 45 frame and adapted to engage the fabric 50 rolls on the said unwinding rollers to retard the unwinding of the fabric material.
8. A machine of the class described, comprising a frame, an unwinding roller journaled on the said frame, a winding up roller 55 having a sectional body provided with lugs at the ends, trunnions journaled on the frame and having flanges provided with slots for the reception of the said lugs, and means for holding the said lugs in position 60 in the slots of the said flanges.
9. A machine of the class described provided with an unwinding roller having loose collars, each provided with a clamping plate for engagement with the peripheral face of 65 the roller, and a manually-controlled cam mounted on the said collar and connected with the said plate to move the latter in and out of engagement with the roller.
10. In a machine of the class described, 70 the combination of a winding roller, of a loose collar on the roller and provided with a recess, a clamping plate in the recess and adapted to engage the peripheral face of the roller, and a manually controlled cam 75 mounted in said recess and connected with the said plate.
11. A machine of the class described, comprising a frame, an unwinding roller journaled on the said frame, a winding up roller 80 having a sectional body provided with lugs at the ends, trunnions journaled on the frame and having flanges provided with slots for the reception of the said lugs, a 85 spring-pressed pin extending into the slot of one of the collars, a retaining lug extending into the slot of the other collar, and a spindle journaled on the collar and having an arm supporting the said retaining lug to move the latter into and out of its slot. 90

In testimony whereof I have signed my name to this specification in the presence of two subscribing witnesses.

FRED McLAUREN BROOKES.
